UNITED STATES PATENT OFFICE.

JOHANNES FENERSTEIN, OF NEW YORK, N. Y.

TRUSS.

SPECIFICATION forming part of Letters Patent No. 295,240, dated March 18, 1884.

Application filed November 14, 1883. (No model.)

To all whom it may concern:

Be it known that I, JOHANNES FENERSTEIN, of the city and county of New York, in the State of New York, have invented a new and useful Improvement in Truss-Pads, of which the following is a specification.

My invention relates to that class of truss-pad which has a sheath or covering of india-rubber.

10 My invention consists, essentially, in a truss-pad composed of a solid body or block and a flexible india-rubber sheath or covering centered upon said body by a projection on the one entering a recess in the other, as more 15 fully hereinafter described, the said sheath or covering conforming in shape to the face of the body or block, fitting in contact therewith at all points and secured thereon by its elasticity.

20 In the accompanying drawings, Figure 1 is a sectional view of a plate or portion of a double truss carrying two pads which embody my invention. Fig. 2 is a face view of the body-piece or block which forms a part of the 25 truss. Fig. 3 is a face view of a body or block of slightly modified form; and Fig. 4 is a sectional view of a pad embodying my invention, but slightly modified in construction.

Similar letters of reference designate corresponding parts in all the figures.

In all cases I make my pad of a solid body or block, A, and a sheath or covering, B. The body or block A may be made of wood or analogous rigid material, and has a convex 35 face and a back which is approximately flat; but the sheath or covering B is made of flexible india-rubber, and conforms in shape to the face of the body or block, so that it will fit in contact therewith. The sheath or covering B, I prefer to mold wrong side out, or I turn it wrong side out, as shown in dotted lines in Fig. 1, and I then place it on the body or block A by turning it over the same, or right side out, as shown in full lines in Figs. 1 and 45 4. It will then be retained in place by its elasticity. In order to properly center the sheath or covering on the body or block, and prevent its slipping out of place while turning it right side out over the block, I connect 50 the sheath or covering with the block by a projection, a, on the one fitting in a recess, b, in the other. As shown in Fig. 1, the projec-

tion a is formed on the rubber sheath or covering, and the recess b in the face of the body or block; but a similar result would be obtained if the recess were formed in the sheath or covering, and the projection on the face of the body or block, and less rubber would be required in making the sheath or covering.

In order to economize rubber, I may form an 60 annular projection, a', on the inner side of the sheath or covering, and the body or block may then have an annular recess or groove, b', formed in it to receive said annular projection, such construction being shown in Fig. 4. 65

The body or block A may be circular, as shown in Fig. 2, or it may be elliptical, as shown in Fig. 3, or of any other suitable shape; and the recess b may be round, as shown in Fig. 2, or elongated, as shown in Fig. 3. 70

In some cases, where additional pressure is desired on a very small surface, I may provide the sheath or covering B with an external projection, c, as shown in Fig. 1, and such projection may be formed integral with the sheath 75 or covering, or attached thereto in any suitable way.

The improved pad herein described is desirable because of its simplicity and small cost, and while being sufficiently rigid it is 80 still somewhat yielding, because of the india-rubber sheath or covering, which conforms in shape to the body or block and is supported thereby.

C designates a piece or plate of metal to 85 which the two pads of a double truss are secured, and which may overlap the edge of the sheath or covering, as shown in Fig. 1, and secure the same. The piece or plate C may be secured to the pads by screws d, in the 90 usual way.

The pad or pads may be finished by covering with chamois-leather.

I am aware that it is not new to make a truss-pad of a disk of sheet metal struck up into 95 concavo-convex form and covered on both sides, or throughout its whole surface both inside and outside. I am also aware that it is not new to make a truss-pad of a back consisting of a series of radial spring-arms connected to a central metal plate, the springs and central plate being bent so as to give them a dome-like figure, a spiral spring bearing on the central plate, and a covering of vulcanized 100

india-rubber. I do not claim either of the pads above described as included in my invention. My pad is composed of only two parts—namely, a solid body or block, A, having a convex face and an approximately flat back, and a sheath of india-rubber conforming to the face of the body or block and fitting in contact therewith at all points. Such a body is much less expensive than a body of thin metal struck up to give it the desired shape, and a solid body or block is more durable than a body or skeleton consisting of a plate having radial spring-arms and a spiral spring bearing on said plate.

15 What I claim as my invention, and desire to secure by Letters Patent, is—

The truss-pad consisting of a solid body or block, A, and the flexible india-rubber sheath or covering B, centered upon said body by means of a recess and projection, as herein described, the said sheath or covering conforming in shape to the face of the body or block A, fitting in contact therewith at all points and secured thereon by its elasticity, substantially as set forth.

JOHANNES FENERSTEIN.

Correction in Letters Patent No. 295,240.

Affidavit having been filed showing that the name of the patentee of Letters Patent No. 295,240, granted March 18, 1884, for an improvement in "Trusses," should have been written and printed *Johannes Feuerstein*, instead of "*Johannes Fenerstein*", it is hereby certified that the said Letters Patent should be read with this correction therein to make it conform to the record of the case in the Patent Office.

Signed, countersigned, and sealed this 22d day of July, A. D. 1884.

[SEAL.]
